UNITED STATES PATENT OFFICE.

CECIL B. HARRISON, OF LOS ANGELES, CALIFORNIA, ASSIGNOR TO JAMES L. DAVIDSON, OF LOS ANGELES, CALIFORNIA, DOING BUSINESS AS J. L. DAVIDSON CO.

POSTLESS LEDGER BINDER.

Application filed January 21, 1924. Serial No. 637,550.

To all whom it may concern:

Be it known that I, CECIL B. HARRISON, a citizen of Great Britain, residing at Los Angeles, California, have invented a new and useful Postless Ledger Binder, of which the following is a specification.

This invention relates to ledgers and has for an object to provide a postless ledger binder.

Another object is to provide a ledger binder of few and simple parts of such construction and arrangement that they will withstand rough and long use.

A further object is to provide a ledger binder having a minimum number of moving parts which are readily operable and very effective in clamping position, and in this connection, an object is to provide operative parts which cannot be dislodged and lost from the binder, and in which the operating parts cannot be disconnected or overthrown during operation.

An object is to provide an organized backbone and clamping means in a ledger binder all of inexpensive, stock material.

An object is to provide a ledger binder having surface protecting means whereby to prevent marring of a finished desk, counter or other supporting plane upon which the ledger may be placed for use, filing or storing, and for the purpose of reducing noise occasioned by and in placing and handling the ledger on a supporting plane.

Other objects and advantages will be made manifest in the following specification of an embodiment of the invention illustrated in the accompanying drawing, wherein:

Fig. 1 is a perspective of the rear of the ledger back with leaves.

Fig. 2 is a perspective showing the interior of the binder.

Fig. 3 is a longitudinal section of the binder: the leaves being omitted.

Fig. 4 is a transverse section showing the clamp bar fully retracted.

Fig. 5 is a transverse section showing the bar in effective clamping position.

Fig. 6 is a perspective of the dismounted clamp bar.

Fig. 7 is a detail view of a corner structure of the back.

Fig. 8 is a detail section of the hinge eye attachment, and an applied cover member.

The illustrated embodiment of the inven-

tion comprises a shell having a back-bone or panel 2, having longitudinal side flanges 3, and parallel flanges or ends 4, preferably all formed of a single piece of sheet metal. The ends of the flanges 3, are formed with flaps 5, bent around the upstanding end flanges 4, to brace the same. The flanges 3, also have longitudinally extending, inturned lips 6, and the corners of the ends 4, are recessed at 7, to receive the lips 6. This forms a rigid and substantial box or back-bone structure.

The binder is provided with a part forming a flat platen and this, as shown, consists of an inner platen device in the form of inwardly faced plates 9, in a common plane and which are shown as longitudinally spaced from each other. The plates 9, are rigidly secured in the back-bone and as shown have downturned side flanges 10, to one of which is secured a bearing strip 11, and to the other of which there is secured a bearing piece 12. Extending transversely across the back-bone of the binder is a substantial screw 13, one end of which turns in the bearing strip 11, and the other end of which is reduced and projects through the bearing piece 12.

The bearing piece 12, is cut away to expose the square head 14, of the screw 13, and the contiguous flange 3, is provided with a key-hole 18, for the insertion of a key K, whereby the screw may be turned when it is desired to clamp leaves L, in the binder. The screw is prevented from endwise movement between its bearing members 11, and 12, which are rigid in the back-bone.

To effectively clamp leaves L, in the binder there is mounted on the screw a slide 15, which is shifted along the screw when the latter is rotated. Rigidly connected to the slide is an upstanding clamp bar 16, of suitable length and which extends longitudinally above the platens 9, upon which the back edges of leaves abut and are aligned 100 as shown in Fig. 5. Opposed to the shiftable clamp bar 16, is a rigid leaf support 17, which extends longitudinally and contiguous to one side flange 3.

The clamp bar 16, when fully retracted 105 recedes beneath the lip 6, of the outer side of the back-bone with respect to the fixed support 17, and this provides for the insertion of leaves in a stack having a thickness about equal to the distance between the lips. To 110

provide for this recession of the clamp bar 16, this is shown as connected in off-set relation to the slide 15; the bar having an angle ledge 18, lying between the edges of the spaced platens 9, and being attached to the slide 15.

It will be seen that the binder consists of two relatively movable members; the screw 13, and the clamping device 16, mounted thereon. It will be seen also that ledger leaves L_2 may be securely fastened in place in the binder without the utilization of any posts or other parts penetrating the leaves, and therefore enabling the ready insertion 10 and removal of leaves in any position in the stack. Also, the moving parts are so connected that they cannot become dislodged from the binder.

A feature of the invention consists of cushioning means to reduce noise and also protect finished surfaces upon which the ledger may be imposed while in use or storage. Such means is shown as including rubber, or other cushion material, cushions 20, suitably secured preferably at the ends of the shell and projecting laterally and rearwardly so as to be effective in the different positions of the binder.

The cover-backs C, of any suitable type 30 may be hingedly connected to hinge-eyes 21, provided along the flanges 3. These hinge-eyes have ears 22, extending through the lips 6, and which are riveted at 23, to the flange 3.

The slide 15 extends endwise under the inwardly spaced platen plates and the ends of the clamp bar 16 in a like manner extend over the platens. From this it will be seen 40 that there are no posts or parts of any character passing through or into the leaves, and that the leaf space above the platens is clear for the ready insertion of leaves in a uniform pile or stack.

The end portions of the slide and the clamp bar are spaced so as to receive the in-

terpositioned platens, which serve to guide the moving clamp device.

What is claimed is:

1. A loose-leaf, book-binder having a back-box including fixed, parallel side walls, an inner false back having a platen face for leaf edges, a jaw shiftable laterally toward one side wall to clamp leaves thereagainst, and means lying between the box back and the inner false back for actuating the clamp-jaw. 55

2. A loose-leaf, book-binder including a back-box having longitudinal side walls, one of which forms a side support for leaves; an inner false back forming a leaf-edge 60 platen, a screw journaled between the back of the box and the false back and operable by a key insertable through one of said side walls, and a clamp jaw in front of the platen face and connected to the screw for adjustment toward either of said walls. 65

3. A book-leaf binder including a back-box having an outer back and an inner back with a platen face for leaf edges, and longitudinal side walls, a clamping bar in front 70 of the platen face, and a transverse screw disposed wholly between the said backs and carrying and operating the bar laterally.

4. A book-leaf binder including a book-back box having a side wall forming a leaf 75 support and a recessed wall opposite said support, a platen part for leaf edges, a leaf-clamping bar movable toward said support to clamp leaves and retractable into the recessed wall, and means for moving said bar. 80

5. A book-leaf binder including a book-back box having parallel side walls, an inner false back having a platen face for leaf-edges, a slide extending longitudinally under the platen back, a transverse screw for operating the slide, and a leaf-engaging means attached to the slide and extending over and along the platen. 85

CECIL B. HARRISON.
